RIVETLESS CHAIN LINK

Leonard T. Harris, Chicago Heights, Ill., assignor to Poor & Company, Chicago, Ill., a corporation of Delaware

Filed Jan. 31, 1962, Ser. No. 68,589

Term of patent 14 years

(Cl. D54—3)

FIG. 1 is a perspective view of a rivetless chain link showing my new design.

FIG. 2 is a horizontal cross-section taken on the line 2—2 of FIG. 1.

FIG. 3 is a vertical cross-section taken on the line 3—3 of FIG. 1.

I claim:

The ornamental design for a rivetless chain link, as shown.
